UNITED STATES PATENT OFFICE.

DAISY GRESHAM LEE, OF CLERMONT, FLORIDA.

PLAYING-CARDS.

1,269,099.

Specification of Letters Patent. Patented June 11, 1918.

Application filed September 15, 1917. Serial No. 191,590.

To all whom it may concern:

Be it known that I, DAISY GRESHAM LEE, a citizen of the United States, residing at Clermont, in the county of Lake and State of Florida, have invented certain new and useful Improvements in Playing-Cards, of which the following is a specification, reference being had to the accompanying drawings:

10 This invention relates to improvements in playing cards and has for its primary object to provide a deck of playing cards divided into sets, the cards constituting each set when placed together, making up the United States flag.

It is another object of the invention to provide a card deck as above characterized for the playing of a game, which will arouse the patriotic sentiments of the participants 20 therein and will provide a very novel and interesting amusement.

It is also another object of my invention to provide in addition to the several sets of playing cards above referred to, additional 25 honor cards each containing one or more complete flags to be counted in the score of the player holding the same.

With the above and other objects in view, my invention consists in the novel features 30 of construction, combination, and arrangement of parts to be hereinafter more fully described, claimed, and illustrated in the accompanying drawing, in which,

Figure 1 illustrates four of the cards in a 35 set having different numbers of stars thereon.

Fig. 2 is a similar view of the two other cards in each set having stripes printed thereon; and

40 Fig. 3 is a view illustrating the four honor cards in the deck.

My improved card game consists of seventy-six cards. In the card deck there is included twelve identical sets of cards, each set consisting of six cards. I have shown one of these sets of cards in Fig. 1 of the drawing and it is to be noted that one card contains three stars, the second ten stars, the third fifteen stars, and the fourth twenty stars. 45 Thus, four of the cards in each set together having a total of forty-eight stars indicated thereon corresponding to the number of stars representing the several States comprised in the Republic of the United States.

In addition, each set of cards includes one 55 card with six stripes thereon and one card with seven stripes, these two cards together containing thirteen stripes as in the United States flag representing the thirteen 60 States of the original American Union. Preferably, the cards containing the stars are provided with a blue background, the stars and the numbers shown in the corners of the card being white. The cards having the seven 65 stripes are white with red stripes, and the cards with six stripes are white with gold stripes, so that these two cards of each set may be readily distinguished from each other.

In addition to the twelve sets of cards 70 above referred to, the card deck includes four honor cards which have one, two, three, and four complete United States flags printed thereon respectively. These honor cards are illustrated in Fig. 2 of the drawing.

The object of the game is for the player to obtain sufficient cards to make up the greatest number of complete flags, after all of the 80 cards have been played in accordance with the prescribed rules. These rules are as follows.

The game should be played by from three to six players. The cards are first thoroughly shuffled and dealt, one at a time, until eight 85 cards have been distributed to each player. The remaining cards are placed upon the table to be drawn from. Each player examines the cards dealt him to see if his hand contains any of the honor cards or a complete set consisting of six cards having three, ten, fifteen, and twenty stars respectively, and six and seven stripes respectively thereon. If so, these cards are laid aside and the player then draws sufficient cards from those 90 in the remainder of the deck to again make up his hand with eight cards. If he draws a prize card, this is laid aside and another card drawn. After all of the players have thus drawn from the deck, if necessary to 95 make up a complete hand, the player at the left of the dealer then draws a card from the person at his right, and if this card which he draws enables him to make up a complete flag, he lays these cards aside and 100 again draws sufficient cards from the table to complete his hand. Then the next player on the left proceeds in the same manner.

This operation continues until all of the cards have been taken from the table, and have been formed into the complete flags. The player who has succeeded in making up the greatest number of flags from cards in his possession, counting the prize cards as representing one, two, three, and four flags respectively, is declared the winner. If it should chance that the last player or players have one or more cards still remaining in their hands after all cards have been drawn, these cards are given to the one holding the largest number of cards and, together, they will make out the last complete flag.

From the foregoing description, taken in connection with the accompanying drawing, it is believed that my improved card game will be clearly and fully understood. The interest of the participants in the game is centered in amicable rivalry in completing the largest number of flags from the broken card sets, and arouses the patriotic spirit and enthusiasm of the individual. In the drawing, I have disclosed the preferable arrangement of the stars and stripes on the flags of the several cards, but it will be understood that the drawing is merely illustrative and these indicative features may be otherwise arranged. The cards can also be provided with additional surface ornamentation of a patriotic character, and the backs or reverse sides of the cards can likewise be provided with any desired ornamental design. It is, therefore, to be understood that in practice, I reserve the privilege of resorting to various minor changes in detail and design, which may be fairly considered within the spirit and scope of the invention as claimed.

Having thus fully described my invention,

Copies of this patent may be obtained for five cents each, by addressing the "Commissioner of Patents, Washington, D. C."

what I desire to claim and secure by Letters Patent is:

1. A pack of cards comprising a plurality of sets of cards, each set consisting of a series of cards certain of which are provided with stars differing in number and certain other cards in each set having different numbers of stripes thereon, one complete set of cards making up the forty-eight stars and thirteen stripes of the United States flag. 45 50

2. A pack of cards comprising a plurality of sets of cards, each set consisting of a series of cards certain of which are provided with stars differing in number and certain other cards in each set having different numbers of stripes thereon, one complete set of cards making up the forty-eight stars and thirteen stripes of the United States flag, and additional honor cards each having one or more complete United States flags delineated thereon. 55 60

3. A pack of cards consisting of seventy-six cards including twelve sets of cards each consisting of six cards, four cards in each set have different numbers of stars thereon and the two remaining cards of each set having different numbers of stripes thereon, the six cards in each set together making up the forty-eight stars and thirteen stripes of the United States flag, and four additional honor cards having one, two, three, and four complete United States flags delineated thereon respectively. 65 70

In testimony whereof I hereunto affix my signature in the presence of two witnesses. 75
